ROSARY ATTACHMENT FOR A WRIST WATCH

Arthur Gilbert Trudeau, 4940 Bayard St.,
Pittsburgh, Pa.

Filed June 22, 1965, Ser. No. 85,875

Term of patent 14 years

(Cl. D42—8)

FIGURE 1 is a front elevational view of a rosary attachment for a wrist watch showing my new design wherein the rosary attachment is for rectangular watch crystals;

FIGURE 2 is a side elevational view thereof;

FIGURE 3 is an enlarged fragmentary view taken on line 3—3 of FIGURE 1;

FIGURE 4 is a modified form of a rosary attachment for a wrist watch wherein the rosary attachment is for circular watch crystals;

FIGURE 5 is a side elevational view thereof.

The broken line showing of the watch face and casing is for illustrative purposes only.

The design comprises a plain cross and ten beads embossed on the surface of a border for the wrist watch and extending therearound, the cross being within the confines of the border, the long axis of the cross parallel to the short axis of the border, substantially as shown.

I claim:

The ornamental design for a rosary attachment for a wrist watch, substantially as shown and described.
